UNITED STATES PATENT OFFICE.

BEN A. BALL, OF PAWTUCKET, RHODE ISLAND, ASSIGNOR TO AMERICAN TEXTILE COMPANY, INC., OF PAWTUCKET, RHODE ISLAND, A CORPORATION OF RHODE ISLAND.

DESIGN FOR LACE DOILY.

Application filed January 30, 1929. Serial No. 29,850. Term of patent 7 years.

To all whom it may concern:

Be it known that I, BEN A. BALL, a citizen of the United States, and a resident of Pawtucket, in the county of Providence and State of Rhode Island, have invented the new, original, and ornamental Design for a Lace Doily, of which the following is a specification.

Reference is had to the accompanying drawing, in which—

The figure is an elevation of a lace doily, showing my new design.

I claim:

The ornamental design for lace doily, substantially as shown.

Signed at Pawtucket, in the county of Providence and State of Rhode Island, this 28th day of January A. D. 1929.

BEN A. BALL.
